Application August 23, 1939, Serial No. 291,626

4 Claims. (Cl. 302—56)

Freshly printed sheets of paper or like material frequently require that they be piled or stacked immediately after the printing operation. When so piled or stacked, considerable weight or pressure is placed on the freshly printed sheet by those sheets stacked above it, particularly near the lower portion of the pile or stack. This weight or pressure is sometimes sufficient to cause a transfer of some of the ink from a freshly printed sheet to the surface of the sheet laid on or against it. This is known in printing parlance as "offset" and is, of course, objectionable from every standpoint.

One very essential factor in the application of materials to a freshly printed sheet is the preparation of the medium to be applied to the sheet, so that a uniform, predetermined and evenly distributed quantity can be applied to the sheet surface.

Due to the objectionable feature of mixing liquid with the material many attempts have, therefore, been made to apply some suitable material directly to the sheet surface without using a liquid vehicle as a conveying means. Such attempts have in the past only been partially successful due very considerably to the improper or incomplete preparation of the material before it is delivered or projected on the sheet. The projection of material, without a liquid conveying vehicle is usually accomplished by a jet of air, the offset eliminating material being mixed with this air in a predetermined and controllable quantity. For any effective use of this method, the material must be mixed very uniformly with the air at all times, and as only a very minute quantity of certain materials are necessary for offset elimination if properly deposited on the sheet, and the problem of mixing these most efficient materials with air, uniformly and in controllable amount, has been one which has not heretofore been satisfactorily solved.

My invention herein described provides an apparatus for, and method of mixing various offset elimination materials with air in any predetermined quantity, or ratio of material and air, of insuring that all material delivered with the air is properly prepared and of proper and suitable particle size, and of maintaining a proper ratio of material and air under all conditions, so long as the apparatus is supplied with proper materials in bulk form. The materials ordinarily used may include many finely divided or powdered materials such as talc, French chalk, soapstone, China clay, barium, alumina, calcium, magnesium, titanium, silicates, starches, zinc, etc.,

some of these being used in the form of carbonates, oxides, sulphides, or hydrates, individually or in combination.

In my apparatus, bulk materials are introduced into the lower section of a suitable container, these materials are properly broken up by mechanical agitation, a portion of the material which has been divided or broken up is separated from the coarser material and transferred to the upper section of the container, it is again treated to remove any coarse or lumpy material and mixed with a predetermined and controlled quantity of air, after which it may be withdrawn or discharged to or on printed sheets for offset elimination purposes.

Reference is made to the following figures:

Fig. 1, sectional elevation through container agitator and air control valves, taken on line 1—1, Fig. 2;

Fig. 1^a is a section showing the valve in a different position;

Fig. 2, plan view of container viewed from line 2—2, Fig. 1;

Fig. 3, sectional elevation through lower portion of container, with agitator raised;

Fig. 4, sectional plan view through container and agitator on line 4—4, Fig. 1;

Fig. 5, power operating means and section through agitator level control chamber;

Fig. 6, cross section through connecting rod on line 6—6, Fig. 5;

Fig. 7, cross section through agitator level control chamber with container having maximum supply of bulk dust material;

Fig. 8, section through agitator level control chamber when chamber has minimum supply of bulk dust material.

My apparatus consists of a bottom container section 1 and a top container section 2 which are secured together by means of flanges 3. These sections form a closed tank or chamber in which the bulk material S is mixed with air in proper ratio or relative proportion as desired and controlled by the operator.

The material in bulk form is introduced through filler plug opening 4, passing downward through the tank section 2, internal cone section 5, down over the outside of agitator 6 to the bottom portion of the tank as shown at S.

The agitator 6 consists of a conical portion 7 and a vertical flange portion 8 and somewhat above the lower edge of this flange is stretched a coarse mesh screen 9. This cone-shaped agitator 6 is moved up and down in a vertical direction by rod 10, said rod being secured to agi-

tator 6 by any suitable means such as a threaded portion on the end of rod 10, and nuts 11. Agitator rod 10 is supported at the top of tank by internal and external guide members 12. The rod is sealed air-tight by packing 13 secured in place by gland 14. If desirable, a replaceable bushing 17 can be inserted in guide members 12 and held in place by screw 18. On the upper end of the rod is a yoke 19 pivotally secured by pin 19a to the bottom end of cylinder 20. Passing through the top of cylinder 20 is a piston rod 21 to which is secured a piston 22, the top of cylinder 20 being closed by cap 23 with packing and packing gland 24 providing an oil tight seal for the rod 21. The piston 22 is provided with holes or passages 26 with a valve 25 overlying these holes or passages on the top of the piston permitting the fluid in the cylinder to pass up through the holes from the bottom of the piston to the top, but preventing the oil or other liquid from passing downward through these holes 26 to the bottom part of the cylinder or below the piston.

The piston 22 is moved up and down by rod 21 operated by means of lever 27 pivoted at 28 in mounting bracket 29, and connected at one end by pin 30 with piston rod 21. The opposite end of lever 27 is moved or oscillated by means of a motor or other suitable mechanism 31, operating through a crank 32, crank pin 33 and connecting rod 34 attached by means of pin 35 to lever 27. Lever 27 may be slotted, as indicated at 36, so that the relative angular oscillation or movement of lever 27, and the resulting vertical motion of pin 30, rod 21 and piston 22 may be varied. Motor 31 is secured to the top of container section 2 by mounting bracket 37.

It will thus be seen that the operation of motor 31 will cause the lever 27 to oscillate which, in turn, causes the vertical reciprocation of agitator 6 in the bottom of the container through the fluid connecting medium F contained in cylinder 20 as will be hereinafter described in greater detail.

Air is supplied to the container sections 1 and 2 through a control and pressure regulating valve 38, the air passing through this valve in the direction of the arrows to a distributing valve 39. In Fig. 1, the air from the pressure regulating valve 38 enters the hollow central portion 41 of adjustable plug 40, passing outwardly therefrom through opening 42. In the plug position shown in Fig. 1, the air, passing through opening 42 is equally divided in space 45, passing in the direction of the arrows to openings 43 and 44 in the outer section of valve 39, the air from opening 43 being connected by suitable piping to air inlet 16 in container section 2, and from opening 44 by suitable piping to inlet 15 in container section 1. Air may be so introduced as to maintain the container interior under substantial pressure.

In Fig. 1a illustrating another position of valve 39, the adjustable plug portion 40 has been moved in such a manner that the opening 43 is closed so that no air can pass from the valve 40 to the container inlet pipe 16. All of the air, therefore, passes thru valve opening 44 to container pipe 15 as shown by the arrows.

It is obvious that any intermediate adjustment of plug section 40 in valve 39 will enable the proportion of air supplied from the pressure regulating valve 38, to be divided between container inlet pipes 15 and 16 in any desired proportion or ratio, from all of the air being supplied to

pipe 15 with no air being supplied to pipe 16 or a condition just the reverse.

The inlet pipe 15 enters the container section 2 at a somewhat lower level or elevation than pipe 16. Between these elevations is interposed an inverted open-end cone member 5, the opening 5a being in its downwardly projecting apex, and providing an open connection between the thusly divided container sections 46 and 47. The inverted cone 5 is secured about its periphery to the wall of container section 2 so as to make an air-tight joint.

Assume that bulk material has been supplied to the container through filler plug 4, and has found its way as previously described into the bottom section 1 of the container as shown at S. Assuming that it is now desired to secure a supply of finely divided powdered material mixed with air for deposition on a freshly printed sheet, the motor 31 is placed in operation which in turn causes a vertical reciprocation of rod 10 and agitator 6. The agitator 6 alternately takes a position as illustrated in Fig. 1 periodically being raised to a position as illustrated in Fig. 3 so that the projecting flange 8 is raised above the level of material S in the bottom of the container. When the agitator 6 again moves downward its vertical edge or rim 8 encounters the surface of the bulk material S entering it for a short distance, and as it enters, the air trapped in the interior or cone portion 7 is blown downwardly, outwardly and upwardly as indicated by the arrows, thereby projecting a cloud of the bulk material mixed with air upwardly into zone 46. This operation is periodically repeated with the result that the space or zone 46 becomes charged with pulverized and finely divided bulk material, discharged into and maintained in zone 46 by the mechanical action of member 6.

The coarse screen section 9 which is stretched across the vertical section 8 somewhat above its lower edge prevents the bulk material from building up in cone shape inside of the agitator 6, the mesh of this screen being so proportioned that it will flatten out the bulk material on each downward stroke, but is sufficiently coarse so that none of the bulk material will be lifted by it on an upward stroke.

After the agitator has been in operation for a brief interval, zone 46, as has been previously described, will have been charged with bulk material, the more finely pulverized or divided materials remaining suspended in the air, and the heavier materials falling downwardly over the outside of the cone section 1 and back onto the surface of the bulk material where they may be again agitated, reduced in size and projected upwardly.

The pressure regulating valve 38 is then opened to admit air under such pressure as the valve may be adjusted to by the operator, this air passing through distributing valve 39 to inlet pipes 15 and 16 as previously described. Assuming that the plug 40 of valve 39 is set as shown in the upper view, air will be admitted in equal proportions through inlet pipes 15 and 16 to the interior of container 2. The air which enters the container through pipe 15 cannot escape downwardly, therefore passes upwardly through opening 5a in the inverted cone 5 or from zone 46 into zone 47 in the direction indicated by the arrows.

It will be noted that both pipes 15 and 16 enter the tank tangentially, resulting in a whirling or spinning action of the air inside of the container 2, which will further segregate the finely di-

vided bulk materials from the coarser particles, the coarser particles falling downwardly along the wall of container section 2 back to the surface of the bulk material, while the finer materials are carried towards the center of the container, and pass upwardly from zone 46 to zone 47.

Air is also entering container section 2 through pipe 16, and entering the tank at an angle induces a circular or spinning motion in the same direction as given the air in zone 46. Any coarse particles or lumps will therefore be carried outwardly to the container wall and drop down this wall and down the inclined wall of cone 5, and back to the agitator for retreatment. This air entering container section 2 through pipe 16 is at the same pressure as regulated by valve 38 as the air entering pipe 15 into zone 46, therefore, the air entering zone 47 through pipe 16 cannot escape downwardly through opening 5a in inverted cone 5 and therefore builds up a pressure in container section 2 corresponding to the regulation of valve 38 or escapes through outlet pipe 48 at or near the top of container section 2. The outlet pipe 48 may be connected to any suitable distribution or application means for applying or distributing the finely divided material contained in the air on or to the freshly printed sheet or other material which it is desired to protect against printing offset. This distribution or application means forms no part of the present invention.

Under the conditions just described, the agitator 6 will continue to charge zone 46 with pulverized bulk material and air entering zone 46 through pipe 15 will assist in the segregation of the fines from the coarse, and discharge the fine particles upwardly through opening 5a into zone 47. If a very considerable quantity of air enters zone 46 through pipe 15 a corresponding quantity of finely pulverized material will be transferred from zone 46 to zone 47.

If, on the other hand, a lesser quantity of air is supplied through pipe 15 to zone 46 a corresponding lesser quantity of finely divided pulverized material will be transferred from zone 46 to zone 47.

Assuming that a certain quantity of air in which is mixed the finely divided materials, is to be discharged from outlet pipe 48 this being regulated by the operator by pressure control valve 38, it is obvious that the air leaving the tank through outlet pipe 48 must enter the tank either through pipe 15 or 16 or through them jointly in some ratio of air quantity. Distributing valve 39, being interposed between the supply and pressure regulating valve 38 and container 2, permits the quantity of air entering container 2 to be divided in any desired ratio or proportion between pipes 15 and 16, or to zones 46 and 47. If the valve 39 is adjusted as shown in the lower view, no air being allowed to enter zone 46 through pipe 15, all of the air escaping through outlet pipe 48 will find its way into container section 2 through pipe 16 and zone 47. Under this condition, there will be no air flowing into zone 46 and consequently no air passing upwardly through opening 5a into zone 47 and consequently no finely divided bulk material being transferred from zone 46 into zone 47.

The motion of the agitator 6 while maintaining a charged condition of air and pulverized material in zone 46, does not, however, cause any transfer of air or material from zone 46 to zone 47 as no circulation between these areas can be

established by the motion of agitator 6 and consequently no transfer of material from one zone to the other. Under these conditions, substantially clear air would be discharged from outlet pipe 48, as zone 47 would be supplied only with clean air through pipe 16.

However, if the adjusting member 40 of valve 39 is moved so that a small quantity of air is admitted to pipe 15 while still admitting the major portion of the air necessary through pipe 16 a small quantity of finely divided material will of necessity be transferred, as previously described, from zone 46 to zone 47 which quantity of air will be supplied with the greater quantity of air supplied through pipe 16 both escaping through outlet pipe 48. If the adjustment of valve 39 is such that all of the air through supply and regulating valve 38 is admitted to container section 2 through pipe 15, the concentration of finely divided materials in zone 47 will speedily become the same as in the central portion or zone 46, and a greater ratio of material with air will be discharged from pipe 48.

Many previous attempts have been made to 25 pulverize the bulk material and mix it with air by means of an air jet, either projected downwardly against the surface of the bulk material or upwardly through the material itself. Either method of air application for breaking up the 30 bulk material is unsatisfactory and insufficient as the bulk material may at times break up rather easily, resulting in the air picking up and carrying with it a great quantity of the material, or at other times, the material may resist the action of the air blown on its surface, or build a channel up through the material from a bottom inlet to the top of the material so that a very much less quantity of this material is picked up and carried away by the air current. Similarly, if more or less air, or air at greater or less pressure is supplied, this will immediately change the amount of materials picked up and carried away. Such variations are not permissible, as they result in either too little or too much material being present in the air or which may be distributed over a sheet, and such variations are out of control of the operator and no means is available to him for making any permanent correction, as conditions within the tank may change even as he may change some exterior adjustment, thereby upsetting and nullifying anything which the operator did or can do. Such an arrangement for supplying air containing minute particles for offset elimination, is, therefore, entirely inadequate and useless.

However, employing a mechanical agitator which mechanically contacts and breaks up the surface of the bulk material, at the same time projecting this material upwardly into a section of a container tank, automatically provides a substantially and consequently uniform charge of mixture of pulverized materials and air which can be drawn upon and diluted with additional air, employing a spinning or centrifugal action to separate any large or unpulverized particles, and thereby provide a uniform constantly maintained ratio and mixture of air and material.

Offset elimination on lightly printed sheets requires only a small quantity of very finely divided materials. Heavier printed sheets will require more material, and it may well be of somewhat coarser texture and the particles larger to effect a greater sheet separation. My apparatus automatically provides this desirable condition, as when only small quantities of material are re-

quired, the mechanical agitator has more time to pulverize the materials, and make them finer. When greater quantities are required, the agitator has less time to pulverize the material, and the greater quantity of air entering zone 46 through pipe 15 will be capable of transferring material having larger particle size from zone 46 to zone 47 than when a lesser quantity of air is admitted through pipe 15 by means of valve 39.

Mention has been made of a slotted portion 36 of lever 27 which provides for adjusting the amount of vertical travel of agitator 6. This permits of adjustment of the mechanical impact and agitating effect of agitator 6 on the bulk material by giving a greater or lesser impact on the material, thereby effecting a greater or lesser degree of pulverizing or breaking up action and a greater or lesser degree of projecting this broken-up material into an area or space where it can be utilized. It is also possible to adjust the speed of motor 31 by any well-known means (not shown) so that the period or rate of impact of agitator 6 on bulk material can be changed, thereby providing the operator with a means of utilizing a wide range of bulk materials S as may be best suited to the particular problems of offset elimination with which he is faced.

Assuming the operator has adjusted either the speed of the motor 31 or the vertical motion of agitator 6, or both, to provide for the most satisfactory operation on the bulk material which he may then be using, he then has available two additional adjusting means for determining the rate at which this material may be utilized, and also the amount of material which may be projected or taken from the container for application to the sheet.

This supply and regulating valve 38 provides a ready means for adjusting the amount of air supplied to the container section 2 which in turn determines the amount delivered from pipe 48 and which in turn enables the operator to control the distance and degree of the distribution of the material. In addition, the distributing valve 39 provides the operator with a ready and easy means of adjusting the amount of air supplied to the heavy particle zone 46 and the light particle zone 47, so that the desired quantity of material, and only the desired quantity, is transferred from zone 46 into zone 47, being thereafter discharged from zone 47 through pipe 48.

It has already been mentioned that the bulk materials are furnished to this apparatus thru filler plug 4, and are deposited or stored in the bottom of container section 1 as indicated at S. It is desirable that sufficient storage space be provided so that the apparatus can be supplied with these bulk materials in sufficient quantity so that they will not need frequent replenishment. It is obvious, of course, that bulk materials being in a compact mass do not require as large storage space, as when they are pulverized and broken up and properly mixed with air in the small quantity necessary for offset elimination; hence a small quantity from a bulk standpoint will produce a very large quantity of air mixture.

This bulk material being stored in the bottom of container section 1 has a natural tendency to settle into a fairly compact body, which further enables more material to be stored for use. The mechanical agitator 6 however, breaks up this compact mass into finely divided particles as has heretofore been described and discharges

these particles into zone 46 where they are picked up by the controlled and regulated air currents. The vertical rim 8 on the bottom of the agitator 6 acts as a pulverizing and breaking member on the bulk material, the coarse screen section 9 stretched across the agitator 6 prevents the material from building up inside the agitator, and further acts to pulverize the center surface area of the bulk material, and the discharge of air from the center cone-shaped area of the agitator ejects this pulverized material upwardly as indicated by the arrows.

It is obvious, of course, that as the bulk material is pulverized, mixed with air, and delivered through outlet pipe 48, that the surface line will gradually be lowered as the material is used up. In order to insure that the flange or rim 8 of the agitator 6 always encounters or impacts the surface of the bulk material in the same manner regardless of the amount of material in container section 1, the cylinder 20 together with the associated parts illustrated in Figs. 5, 7 and 8, is provided. The cylinder 20 is filled nearly to the top with any suitable fluid material such as oil. The piston 22 mounted on rod 21 has a fairly close fit between it and the inner surface of cylinder 20, but, however, with sufficient space between the piston and cylinder so that the oil or other liquid in cylinder 20 can leak or escape between the walls of the piston 22 and cylinder 20 slowly in the direction indicated by the outer arrows in Fig. 5, in case the agitator 6 is not resting or held by its contact with the surface of the bulk material S in container section 1.

The normal weight of the agitator 6 together with rod 10 and cylinder 20 is sufficient to overcome any friction of the rod 10 in passing through the guide 12 or the packing 13 resulting in the agitator 6 always tending to travel or move downwardly unless it is prevented from so doing by its contact with the bulk material S. However, with the motor 31 operating at normal speed, the lever 27 oscillates sufficiently rapidly so that in its upward motion, and carrying with it rod 21 and piston 22, the cylinder 20 is lifted almost as great a distance vertically as the travel of the piston 22, there being, however, a slight leakage by the piston and consequently a slightly less travel upward imparted to cylinder 20. On a return or downward stroke of rod 21 the piston 22 and cylinder 20 move downwardly in substantial unison until the flange 8 of agitator 6 encounters the surface of the bulk material S in the bottom of the container. After sufficient impact has occurred between the agitator and the bulk material as determined by the weight of the agitator and its associated parts, any continued downward travel of the piston 22 will impart no added impact or pressure on the bulk material, as the oil or other liquid F in the lower section of cylinder 20 will escape upwardly as indicated by the arrows, through holes 26, lifting valve 25 and passing into the area or space above the piston. Immediately the piston starts back upward again, the valve 25 closes to insure that the cylinder and agitator be again lifted its predetermined and regulated amount as controlled by the position of pin 35 in slot 36 of lever 27.

Fig. 7 illustrates the relative position of the piston and cylinder in both its upward and downward strokes when the container section 1 has been freshly filled with bulk material to practically its entire capacity. The partial sections of the Fig. 7 indicate schematically the amount of

relative motion between the piston and cylinder on the upward stroke due to leakage of liquid past the piston in a downwardly direction, while the piston is traveling upward. Fig. 8 shows the relative position of the cylinder 20 in its downward position, and the space of travel N shown between the cylinder positions of 7 and 8 shows the normal amount of lift of the cylinder by the piston. It is obvious that the amount of liquid which is bypassed around the piston, can be readily controlled or adjusted by increasing or decreasing the space between the piston and cylinder, or by using a lighter or heavier liquid in the cylinder. While the bypassing or leakage of the liquid around the piston or between it and the cylinder has been described only as applying to the upward stroke of the piston, there may also be a slight leakage on the downward stroke of the piston, as the cylinder may tend to move faster than the piston on the downward stroke as well as slower than the piston on the upward stroke. In any case, this downward motion or slippage of the cylinder accomplishes the same result with the assurance and certainty that the agitator 6 will always contact and impact the surface of the bulk material S in the bottom of the container.

As this bulk material is used up and discharged from the container, the normal relative positions of the piston 22 and cylinder 20 will change from that indicated in Fig. 7 to that indicated in Fig. 8, in which condition the container will be nearly empty, and there will have been discharged through the outlet pipe 48 all of the bulk materials stored in the bottom of the container. The storage space for bulk material may be of any desired depth as determined by the length of the cylinder 20 and the relative piston positions Fig. 7 and Fig. 8.

It will, therefore, be observed that under all conditions the agitator 6 operates in exactly the same manner on the bulk material regardless of whether the tank has been freshly filled or is nearly empty, and there is no difference in the amount or degree of pulverized materials delivered to zone 46 whether the storage of bulk material S be at the maximum container capacity or its minimum capacity.

It will thus be seen that I have provided a novel yet simple apparatus for and method of preparing bulk materials to be used for printing offset elimination. No messy liquid conveying agents are necessary. Any suitable material, or combination of materials in dry bulk form can be used. These materials are definitely and positively broken up and pulverized into the finely divided state necessary for use in complete and efficient offset elimination. In such a finely divided state, the material has no detrimental effect on the printed surface, and my apparatus and method of material preparation and delivery, prevents anything but material of the proper size and fineness from being delivered for use.

Ample storage space for the bulk materials is provided. The apparatus can be operated for long periods of time without stopping to add fresh material. During the use of this large amount of material, there can be no change in the quality or quantity ratio of material delivered with any one setting or adjustment of the apparatus. Adequate adjustments are provided so that the operator can meet and eliminate any offset condition in the most efficient manner. These adjustments are not inter-dependent, nor does one react against another. Rather, each

adjustment feature is so arranged that it acts as an aid to one or more of the others.

For instance, in case of a lightly printed sheet, and where little offset eliminating material is required, the operator may reduce the agitator speed, or its motion, or both, thereby creating a lesser concentration of material in zone 46 and still enable him to use a considerable quantity of air through both pipes 15 and 16, to perhaps effect better distribution over a large sheet. For an extremely heavily inked sheet, the operator may do just the opposite. Or he may be using an ink on which he wishes to use only the minimum of necessary material. Or the sheet may require a second printing, in which case too much, or unnecessary use or excess of material is objectionable. The operator not only has a simple method of controlling quantity of material, but also its fineness or particle size, and this without the necessity of changing the material in the container, or stopping the apparatus.

The method of preparation permits the use of a wide range of materials, or combinations of materials. Some very desirable materials may have a tendency to lump or pack under varying atmospheric conditions, and therefore not be usable with equipment heretofore available. The provision of a mechanical agitator, with variable speed and degree of impact enables the use of materials ordinarily difficult or impossible to handle. Double separation of fines from coarse or lumpy masses insures delivery of only properly prepared material. Control valves for quantity and distribution with dual mixing of the air with the material before it leaves the container, insures evenness and uniformity of mixture, uniformity of particle size, and ready and simple adjustments of both air quantity and ratio of air and material.

In describing my method of preparing materials for offset elimination, I have shown a specification apparatus arrangement. I do not limit myself, however, to this specific design or arrangement of mechanical parts, other than as set forth and within the scope of the accompanying claims.

Having described my invention, what I claim is:

1. Apparatus of the class described, comprising a closed container, an agitating member for pulverizing and agitating material stored in said container, means for operating said agitating member, and means cooperating with said first mentioned means whereby the position of said agitating member is adjusted vertically relative to the material stored in said container, to effect constant and equal pulverizing and agitating action regardless of the amount of material stored in said container.

2. Apparatus of the class described, comprising a container divided into two zones by a partition having an opening therein, a mechanical agitator for pulverizing said bulk material in said lower zone, and for mixing said pulverized material with air, an air jet admitting air to said lower zone effecting a segregation of the finely pulverized material and the discharge of this material with air into the upper zone, and a second air jet admitting air to said upper zone to effect a further segregation of finely pulverized materials and the discharge of said finely pulverized material with air from said second zone and from said container.

3. Apparatus of the class described, comprising a closed container, a partition within said container with walls sloping towards a central opening, and separating said container into upper and

lower zones, a mechanical agitator and pulverizing member operating to pulverize and agitate material contained in the lower zone of said container, an air pipe connected to said container adjacent to said agitator in the lower zone, a second air pipe connected to said container in the upper zone, and means to admit air to said container through said pipes, and to control the relative amount of air admitted through each of said pipes.

4. Apparatus comprising a closed container

5

provided with an outlet in its upper portion, a partition having a central opening dividing the container into upper and lower connected zones to permit passage of the material from the lower zone to the upper zone, a mechanical agitator operating in the lower zone, an air inlet pipe for each zone, and a regulating valve connected to said inlet pipes for controlling the relative amount of air admitted to each container zone.
